CLAIM

The ornamental design for a straw cap, as shown and described.

DESCRIPTION

FIG. 1 is a perspective view of a straw cap showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are shown for the purpose of illustrating both parts of the article as well as environmental subject matter of an exemplary straw. None of the broken lines form part of the claimed design.

1 Claim, 8 Drawing Sheets
